UNITED STATES PATENT OFFICE

2,202,431

MANUFACTURE OF PAPER BAGS

Karl Rohrbacher, Berlin, Germany

Application July 13, 1937, Serial No. 153,426
In Germany July 18, 1936

14 Claims. (Cl. 93—28)

This invention relates to a method of producing block bottoms on flattened paper tubes while being fed in a direction transversely to their length, that is with the open edges parallel to the direction of feed, and to a device for carrying out this method.

The invention consists in opening the leading part of the flattened tube at one end, forcing the sides of the leading part outwardly transversely to the plane of the flattened tube to form a pocket having a side in the form of a right-angled isosceles triangle, rolling the pocket in the direction of feed in a plane at right angles to the plane of the flattened tube, so as to flatten the pocket, and continuing the rolling to turn up the ends of the sides of the flattened tube, thereby forming and flattening a corresponding pocket at the rear part of the tube.

Preferably, during the rolling operation, the pockets and the upturned ends of the tube between the pockets are creased along lines parallel to the plane of the flattened tube and intermediate of said plane and the edges of the upturned ends, so that, for completing the bag bottom, the two end portions extending outwardly from these creases only require to be bent over each by 180° and stuck together.

In the manufacture of so-called valved bags, the continuously fed tube lengths are operated on at both open edges simultaneously in the same manner, the only difference being that at one side provision has to be made in a known manner for the forming of the valve opening.

The invention is illustrated diagrammatically by way of example in the accompanying drawings, in which

Figs. 1 to 5 show a side view (that is at right angles to the direction of feed) in various operative positions.

Fig. 6a shows a detail.

Figs. 6 and 7 are front views of Figs. 1 to 5, Fig. 6 corresponding to Fig. 3 and Fig. 7 to Fig. 4. In order to simplify the illustration some parts are omitted in Figs. 6 and 7.

Fig. 8 is a plan view of Figs. 6 and 7, the position of the parts corresponding to that of Fig. 7.

Fig. 9 is a side elevation of a machine with the front side of the machine bed removed to show the driving mechanism for the various parts, and

Fig. 10 is a perspective view of a machine according to the invention.

Figure 11 is a perspective view showing one of the grippers v_1, v_2 .

The paper tube p which is held down on a feed

table in a known manner and is conveyed in the flattened state horizontally in a direction at right angles to its length first passes between two rollers r_1, r_2 (Fig. 1), which engage the tube at such a distance from the open edge of the tube that a sufficient marginal strip p_1 of the tube p for forming the block bottom projects outwards (Fig. 6).

For limiting the bottom-forming operations to the marginal strip p_1 of the tube p two rails f and i which are parallel to one another serve in a known manner, these rails being shown only in Figs. 6a and 10 and being omitted in all the other figures for the sake of clearness. The lower rail f may be formed by the feed table 10 itself, whilst the upper rail i is made adjustable in the usual way so as to enable its distance from the lower rail f to be adapted to the thickness of the blanks to be operated on.

As soon as the paper tube p has passed between the rollers r_1, r_2 , the leading part of the tube end is opened by suction members s_1, s_2 (Fig. 2) in such a manner that the side walls of the free marginal part p_1 , which have hitherto lain flat on one another, are bent apart 25 in opposite directions. As the suction members s_1, s_2 are mounted on the same shafts w_1, w_2 as the rollers r_1, r_2 and revolve at the same speed as the latter, the suction members s_1, s_2 will 30 detach themselves again from the marginal part p_1 of the tube, when they have turned through a certain angle (Fig. 3).

Previously to the suction members s_1, s_2 detaching themselves, however, two preliminary grippers v_1, v_2 enter the tube part p_1 which has been slightly opened by the suction members s_1, s_2 (Fig. 2), which grippers turn in opposite directions in a plane which is both perpendicular to the direction of feed of the paper tube p and perpendicular to the plane of rotation of the suction members s_1, s_2 (and of the rollers r_1, r_2). The preliminary grippers v_1, v_2 continue the opening of the tube at its marginal part p_1 to an extent which is limited by the nip of the rollers r_1, r_2 (Fig. 3), whereupon two main grippers h_1, h_2 45 act on the tube part p_1 (Figs. 3 and 4 and Figs. 6 to 8).

The two main grippers h_1, h_2 of sickle-like form are mounted on shafts e_1, e_2 which form an angle with the direction of feed of the tube, 50 preferably an angle of 45°. The speed of the main grippers h_1, h_2 , which also turn in opposite directions, is made such that the velocity component acting in the direction of feed of the tube has at least the same value as the speed of 55

feed itself. The main grippers h_1, h_2 during their rotation form at the forward edge of the free part p_1 of the tube a pocket t_1 having a wall, which lies in a plane perpendicular to the plane 5 of feed (Fig. 4).

As soon as the main grippers h_1, h_2 have drawn the forward pocket t_1 so far apart that it has the form of a right-angled isosceles triangle, this pocket t_1 is transferred by the main grippers h_1, h_2 to a pair of rollers a_1, a_2 , which roll out and flatten the pocket t_1 produced by the main grippers h_1, h_2 (Fig. 8). These rollers a_1, a_2 are arranged so as to meet in the plane of the pocket t_1 with their axes a_4, a_5 perpendicular to 10 the direction of feed.

At the inside of the pocket t_1 the roller a_2 is in two parts, as the horizontal main part p of the tube has to pass through here. The externally situated roller a_1 has in the middle a recess a_3 , in order that the pocket t_1 shall not be unnecessarily weakened at its point by being 20 too sharply rolled out. The same applies to the second pocket t_2 which is subsequently produced at the rear edge of the marginal part p_1 .

The main grippers h_1, h_2 arranged on the inclined shafts e_1, e_2 , operate in such a manner that the pocket t_1 is transferred to the rollers a_1, a_2 at the moment at which its production by the main grippers h_1, h_2 is completed, so that the 25 pocket t_1 is never left to itself.

On the paper tube p continuing to advance, the second pocket t_2 is formed at the rear edge of the free marginal part p_1 , as soon as the rollers a_1, a_2 approach the end of the tube owing to 30 the two side walls of the free marginal part p_1 being bent over by 90° in opposite directions during the passage thereof between the rollers a_1, a_2 , so that at the rear edge of the marginal part p_1 a pocket t_2 of exactly the same shape as 35 the forward pocket t_1 , that is to say having the form of a right-angled isosceles triangle, must be formed positively.

The rollers r_1, r_2 may at the same time serve for forming a crease b_1 (Fig. 6) between the free 40 marginal part p_1 and the inwardly lying main part p of the tube. Similarly the rollers a_1, a_2 may form a crease b_2, b_3 in the middle of the vertically extending side walls (Fig. 5), so that, after they have passed through between the rollers a_1, a_2 , it is only necessary, for forming the block bottom, to bend over the outer parts p_2, p_3 of the side walls through 180° to one another. 45

The ribs or grooves provided on the pair of rollers a_1, a_2 for forming the creases b_2, b_3 are 50 preferably adjustable, so as to enable the creases b_2, b_3 to be easily displaced, when the width of the free marginal part p_1 , that is to say the width of the bottom of the bag, is altered. The suction member s , and the preliminary grippers v_1, v_2 should also be coupled with one another in such 55 a manner that the relation between the two parts is always maintained, so that, when the width of the bag bottom is to be altered, the suction members s_1, s_2 and the preliminary grippers v_1, v_2 can also always be pointly adjusted.

The arrangement of the shafts e_1, e_2 for the main grippers h_1, h_2 , such that they form an angle of 45° with the direction of feed of the paper tube p and that the point of intersection of 60 their axes lies in a plane which passes through the axes a_4, a_5 of the two vertically arranged rollers a_1, a_2 , provides the advantage, that the grippers h_1, h_2 will be easily adjustable through being simply displaced on their shafts to the 65 marginal parts p_1 of different width of the paper

tube and therefore to bag bottoms of different widths.

In order, after the forming of the forward pocket t_1 , to assist the proper stretching of the free side walls of the marginal part p_1 in the 5 vertical position, counter pressure cylinders or rollers h may coact with the main grippers h_1, h_2 , which rollers are so arranged behind the side walls which have been bent over by 90° that their axes lie parallel to the corresponding axes 10 of the main grippers h_1, h_2 . This arrangement prevents the stresses set up, during the forming of the forward pocket t_1 , in the part of the marginal portion p_1 lying behind it, causing the blank to enter between the rollers a_1, a_2 on the skew 15 or in a distorted state, which might give rise to folds in the side walls and to the rear pocket t_2 being rolled out askew.

What I claim is:

1. In a method of producing paper bags with 20 block bottoms, the steps consisting in feeding a flattened paper tube in a direction transversely to its length, engaging the sides of the leading part of the flattened tube at one end and forcing the sides of said leading part outwardly trans- 25 versely to the plane of the flattened tube, so as to form a pocket having a side in the form of a right-angled isosceles triangle, rolling said pocket in the direction of feed in a plane at right angles to the plane of the flattened tube, so as to flatten 30 the pocket, and continuing the rolling to turn up the ends of the sides of the flattened tube and to form and flatten a corresponding pocket at the trailing part of the tube.

2. In a method of producing paper bags with 35 block bottoms, the combination of the steps as set forth in claim 1 with the additional step consisting in creasing the pockets and the upturned ends of the tube between the pockets along lines parallel to the plane of the flattened tube and 40 intermediately of said plane and the edges of the upturned ends.

3. For producing paper bags with block bottoms, the combination of feeding means for feeding a flattened paper tube in a direction trans- 45 versely to its length, means for opening the leading part of the flattened tube at one end, a pair of grippers arranged at an inclination to the direction of feed of the tube and rotatable in opposite directions, so as to engage and force the sides of the tube apart and form a pocket at said leading part having a side in the form of a right-angled isosceles triangle, and rollers having their axes extending at right angles to the plane of the flattened tube and arranged to flatten the 50 pocket formed by the grippers, to bend up the sides of the flattened tube adjacent the pocket at right angles to the plane of the flattened tube and form and flatten a corresponding pocket at the rear part of the tube end.

4. For producing paper bags with block bottoms, the combination of feeding means for feeding a flattened paper tube in a direction trans- 55 versely to its length, means for opening the leading part of the flattened tube at one end, a pair of grippers of substantially sickle-shape arranged at an inclination to the direction of feed of the tube and rotatable in opposite directions, so as to engage and force the sides of the tube apart and form a pocket at said leading 60 part having a side in the form of a right-angled isosceles triangle, and rollers having their axes extending at right angles to the plane of the flattened tube and arranged to flatten the pocket 65 formed by the grippers, to bend up the sides of 70

75

the flattened tube adjacent the pocket at right angles to the plane of the flattened tube and form and flatten a corresponding pocket at the rear part of the tube end.

5. For producing paper bags with block bottoms, the combination of feeding means for feeding a flattened paper tube in a direction transversely to its length, means for opening the leading part of the flattened tube at one end, 10 a pair of grippers arranged with their axes at 45° to the direction of feed of the tube and rotatable in opposite directions, so as to engage and force the sides of the tube apart and form a pocket at said leading part having a side in the 15 form of a right-angled isosceles triangle, and rollers having their axes extending in a vertical plane at right angles to the direction of feed and to the plane of the flattened tube and arranged to flatten the pocket formed by the grippers, to bend up the sides of the flattened tube adjacent the pocket at right angles to the plane of the flattened tube and form and flatten a corresponding pocket at the rear part of the tube end.

6. For producing paper bags with block bottoms, the combination of feeding means for feeding a flattened paper tube in a direction transversely to its length, a pair of suction members arranged to draw apart and open the leading part of the flattened tube at one end, a pair of 30 grippers arranged at an inclination to the direction of feed and rotatable in opposite directions, so as to engage and force the sides of the tube apart and form a pocket at said leading part having a side in the form of a right-angled isosceles triangle, and rollers having their axes extending in a plane at right angles to the direction of feed and to the plane of the flattened tube and arranged to flatten the pocket formed by the grippers, to bend up the sides of the flattened 35 tube adjacent the pocket at right angles to the plane of the flattened tube and form and flatten a corresponding pocket at the rear part of the tube end.

7. For producing paper bags with block bottoms, the combination of a pair of feed rollers arranged to engage a flattened paper tube at a point spaced from one end thereof and to feed the tube in a direction transversely to its length, a pair of suction members arranged to rotate in 40 opposite directions coaxially and in unison with said feed rollers for opening the leading part of the flattened tube at one end, a pair of grippers arranged at an inclination to the direction of feed of the tube and rotatable in opposite 45 directions, so as to engage and force the sides of the tube apart and form a pocket at said leading part having a side in the form of a right-angled isosceles triangle, and rollers having their axes extending in a plane at right angles to the direction of feed and to the plane of the flattened tube and arranged to flatten the pocket formed by the grippers, to bend up the sides of the flattened tube adjacent the pocket at right 50 angles to the plane of the flattened tube and form and flatten a corresponding pocket at the rear part of the tube end.

8. For producing paper bags with block bottoms, the combination of feeding means for feeding a flattened paper tube in a direction transversely to its length, a pair of suction members 55

arranged to draw apart and open the leading part of the flattened tube at one end, a pair of preliminary grippers arranged to engage the opened part of the flattened tube and continue the opening movement initiated by the suction members during the continued feed of the tube, a pair of main grippers arranged at an inclination to the direction of feed and rotatable in opposite directions, so as to engage and force the opened sides of the tube apart to form a pocket 10 at said leading part having a side in the form of a right-angled isosceles triangle, and rollers having their axes extending at right angles to the direction of feed and to the plane of the flattened tube and arranged to flatten the pocket formed by said main grippers, to bend up the sides of the flattened tube adjacent the pocket at 15 right angles to the plane of the flattened tube and form and flatten a corresponding pocket at the rear part of the tube end.

9. For producing paper bags with block bottoms, the combination of feeding means for feeding a flattened paper tube in a direction transversely to its length, a pair of suction members arranged to draw apart and open the leading part 20 of the flattened tube at one end, a pair of preliminary grippers arranged for rotation in opposite directions in a plane perpendicular to the direction of feed about axes parallel to the direction of feed, so as to engage the opened part of the flattened tube and continue the opening movement initiated by the suction members during the continued feed of the tube, a pair of main grippers arranged at an inclination to the direction of feed and rotatable in opposite directions, so as to engage and force the opened sides of the tube apart to form a pocket at said leading part having a side in the form of a right-angled isosceles triangle, and rollers having their axes extending at right angles to the direction 25 of feed and to the plane of the flattened tube and arranged to flatten the pocket formed by said main grippers, to bend up the sides of the flattened tube adjacent the pocket at right angles to the plane of the flattened tube and form and flatten a corresponding pocket at the rear part of the tube end.

10. For producing paper bags with block bottoms, the combination of feeding means for feeding a flattened paper tube in a direction transversely to its length, a pair of suction members arranged to draw apart and open the leading part of the flattened tube at one end, a pair of preliminary grippers arranged for rotation in opposite directions in a plane perpendicular to the direction of feed about axes parallel to the direction of feed, so as to engage the opened part of the flattened tube and continue the opening movement initiated by the suction members during the continued feed of the tube, said suction members and preliminary grippers being displaceable in unison in a direction transversely to the direction of feed, so as to enable the suction members and preliminary grippers to be adjusted jointly for varying the width of the bag 50 bottom, a pair of main grippers arranged at an inclination to the direction of feed and rotatable in opposite directions, so as to engage and force the opened sides of the tube apart to form a pocket at said leading part having a side in the form of a right-angled isosceles triangle, and rollers having their axes extending at right angles to the direction of feed and to the plane of the flattened tube and arranged to flatten the pocket formed by said main grippers, to bend up the 55

70

75

- sides of the flattened tube adjacent the pocket at right angles to the plane of the flattened tube and form and flatten a corresponding pocket at the rear part of the tube end.
- 5 11. For producing paper bags with block bottoms, the combination of feeding means for feeding a flattened paper tube in a direction transversely to its length, means for opening the leading part of the flattened tube at one end, a pair 10 of grippers arranged at an inclination to the direction of feed of the tube and rotatable in opposite directions, so as to engage and force the sides of the tube apart and form a pocket at said leading part having a side in the form of a right-angled isosceles triangle, and rollers having their axes extending at right angles to the plane of the flattened tube and arranged to flatten the pocket formed by the grippers, to bend up the sides of the flattened tube adjacent the pocket at 15 right angles to the plane of the flattened tube and form and flatten a corresponding pocket at the rear part of the tube end, the said rollers comprising a pair to engage one side of the pockets and spaced endwise from one another to form 20 a gap for the reception of the main part of the flattened tube.
12. For producing paper bags with block bottoms, the combination of feeding means for feeding a flattened paper tube in a direction transversely to its length, means for opening the leading part of the flattened tube at one end, a pair 25 of grippers arranged at an inclination to the direction of feed of the tube and rotatable in opposite directions, so as to engage and force the sides of the tube apart and form a pocket at said leading part having a side in the form of a right-angled isosceles triangle, and rollers having their 30 axes extending at right angles to the plane of the flattened tube and arranged to flatten the pocket formed by the grippers, to bend up the sides of the flattened tube adjacent the pocket at right angles to the plane of the flattened tube and form and flatten a corresponding pocket at the rear part of the tube end, the said rollers comprising a roller for engaging the side of the 35 pockets remote from the main part of the flattened tube, said roller having a depression midway between its ends for relieving the pressure acting on the portion of said side in proximity to the plane of the flattened tube.
13. For producing paper bags with block bottoms, the combination of feeding means for feeding a flattened paper tube in a direction transversely to its length, means for opening the leading part of the flattened tube at one end, a pair 40 of grippers arranged at an inclination to the direction of feed of the tube and rotatable in opposite directions, so as to engage and force the sides of the tube apart and form a pocket at said leading part having a side in the form of a right-angled isosceles triangle, and rollers having their axes extending at right angles to the plane of the flattened tube and arranged to flatten the pocket formed by the grippers, to bend up the sides of the flattened tube adjacent the pocket at right angles to the plane of the flattened tube and form and flatten a corresponding pocket at the rear part of the tube end, the said rollers comprising a roller for engaging the side of the 45 pockets remote from the main part of the flattened tube, said roller having a depression midway between its ends for relieving the pressure acting on the portion of said side in proximity to the plane of the flattened tube.

5 at right angles to the plane of the flattened tube and form and flatten a corresponding pocket at the rear part of the tube end, the said rollers having coacting ribs and depressions arranged to crease the pockets and the upturned ends of the 10 tube between the pockets along lines parallel to the plane of the flattened tube and immediately of said plane and the edges of the upturned ends.

13. For producing paper bags with block bottoms, the combination of feeding means for feeding a flattened paper tube in a direction transversely to its length, means for opening the leading part of the flattened tube at one end, a pair 15 of grippers arranged at an inclination to the direction of feed of the tube and rotatable in opposite directions, so as to engage and force the sides of the tube apart and form a pocket at said leading part having a side in the form of a right-angled isosceles triangle, and rollers having their 20 axes extending at right angles to the plane of the flattened tube and arranged to flatten the pocket formed by the grippers, to bend up the sides of the flattened tube adjacent the pocket at right angles to the plane of the flattened tube and form and flatten a corresponding pocket at the rear part of the tube end, the said rollers comprising a roller for engaging the side of the 25 pockets remote from the main part of the flattened tube, said roller having a depression midway between its ends for relieving the pressure acting on the portion of said side in proximity to the plane of the flattened tube.

14. For producing paper bags with block bottoms, the combination as set forth in claim 3 35 with counter-pressure rollers arranged with their axes parallel to the axes of the respective grippers so as to engage behind the side walls of the pocket formed by the grippers in the flattened tube.

KARL ROHRBACHER.
